UNITED STATES PATENT OFFICE.

JAMES OTIS WILLIAMSON, OF MONTGOMERY, ALABAMA, ASSIGNOR TO THE SWEET DREAMS COMPANY, OF MONTGOMERY, ALABAMA, A CORPORATION OF ALABAMA.

BOTTLE STOPPER AND CAP.

Application filed July 17, 1922. Serial No. 575,482.

To all whom it may concern:

Be it known that I, JAMES OTIS WILLIAMSON, a citizen of United States, residing at Montgomery, in the county of Montgomery and State of Alabama, have invented new and useful Improvements in Bottle Stoppers and Caps, of which the following is a specification.

This invention relates to improvements in receptacle stoppers and more particularly to sprinkling stoppers for bottles.

Prior to the present invention sprinkling stoppers have been made of metal or glass tubes surrounded by a cork plug. Such stoppers are expensive to manufacture and usually present an unsightly appearance owing to the fact that the material contained in the bottle passes between the tube and the plug after the cork shrinks.

20 The primary object of the present invention is to furnish a sprinkling stopper of inexpensive construction and one which will effectively seal the upper portion of the cork and prevent any of the liquid contained 25 in the bottle from traveling to the exterior of the cork.

Another object of the invention is to provide an attachment for an ordinary cork and this attachment will include a tubular 30 head adapted to be placed on the upper end of the cork, and an ordinary nail which may be passed through the tubular head and through the cork for the purpose of forming a passageway or conduit in the 35 latter.

With the foregoing objects outlined and with other objects in view which will appear as the description proceeds, the invention consists in the novel features hereinafter described in detail, illustrated in 40 the accompanying drawing and more particularly pointed out in the claims.

Referring to the drawing:

Figure 1 is a vertical sectional view of 45 the upper portion of a bottle showing one form of the improved stopper closing the mouth thereof.

Fig. 2 is a perspective view of one form of rod or nail forming part of the construction 50 shown in Fig. 1.

Fig. 3 is a perspective view of the tubular head.

Fig. 4 is a similar view of the cork plug.

Fig. 5 is a vertical sectional view of a 55 modification in which an ordinary nail is employed to seal the tube or passageway.

In the drawing, 1 designates a bottle of any construction provided with a cork plug 2 provided with a central longitudinal passageway or conduit 3. Arranged on the head of the cork or plug is a tubular head or nozzle 4 having a conduit 5 aligned with the conduit 3 of the plug and merging at its upper end into an annular recess 6 adapted to permit the countersinking of the head 7 of the closure rod 8. It will be noted at this point that the head 7 will form a seal with the bottom wall of the recess 6 and will prevent liquid traveling along the rod 79 from reaching the exterior of the tubular head 4.

The upper portion of the tubular head is in the form of a truncated cone with the base arranged uppermost so that the upper 75 portion 9 will in effect form a knob or handle to permit the ready removal of the head and the rod 8, whereby to facilitate the separation of the head from the cork.

The lower portion of the head 4 is provided with a depending skirt or annular flange 10 which surrounds the upper portion of the cylindrical surface of the plug 2 and snugly engages the head of the plug for the purpose of permitting the withdrawal 85 of the head 4 and rod 8. It will be understood that when the bottle is grasped in one hand the head is held by the other hand, the head and rod may be readily removed from the bottle by twisting the head back 90 and forth, this twisting movement causing the rod 8 to be withdrawn from the hole 3 in the plug 2, leaving the latter in the bottle neck.

In addition to the flange 10 forming a 95 means for manipulating the cork by movement of the head 4, the flange 10 also forms a sealing means between the head of the cork and the under surface of the head 4 so that any liquid traveling outwardly from the 100 passageways 3 and 5 between the cork and head will be prevented from reaching the exterior of the stopper.

The head 4 may be made of any suitable

material but it is preferred to make the same of wood as it has been found in practice that the same may be manufactured at a very low cost when made of wood. The wood can 5 be dyed, if desired.

It will be understood that when the rod 8 is in position and the plug is within the mouth of the bottle, the bottle will be effectively sealed, but when the closure member 10 or rod 8 is withdrawn from the passageway 3 the contents of the bottle may be sprinkled from the stopper.

In practice it is advantageous to furnish 15 the stopper shown in Figure 1 with the goods but for the purpose of replacing the plug 2 by any ordinary imperforate cork, it is advisable to use the construction shown 20 in Fig. 5. In this embodiment 2^a designates any ordinary cork plug which may be applied to the rod 8^a by simply forcing the point 8^b of the rod through the cork. This will form a passageway 3^a in the plug 2^a. In this modification the rod is formed of an ordinary nail.

25 From the foregoing I believe that the construction, operation and advantages of the invention will be readily understood by those skilled in the art, and it is apparent that changes may be made in the construction 30 illustrated without departing from the spirit of the invention as expressed in the following claims.

It further is advisable to give some corrugation to the upper part of the rod 8 or 35 8^a which may be of about the same character as the corrugation or roughening of ordinary wire nails, near their heads. This roughening preferably extends downwardly from the head of the nail to about the bottom 40 of the head 4. This makes the nail or rod adhere tightly to the head 4, but slide easily in the hole 3 in cork 2, so as to be readily and easily withdrawn therefrom, leaving the perforated cork in the neck of 45 the bottle to act as a sprinkling top, for throwing a drop or a few drops of the liquid out of the bottle.

What is claimed and desired to be secured by Letters-Patent is:

50 1. A sprinkling stopper comprising an aperture cork plug, a tubular wood head abutting against one end of said plug and having a depending annular skirt snugly engaging the outer surface to said plug, and 55 a removable metal headed rod passing

through the aperture of the tubular head and the perforation of the plug for closing said aperture and perforation.

2. A stopper of the kind defined by claim 1 in which the tubular head is provided with 60 a recess merging into its aperture, and in which the head of said rod is countersunk in said recess.

3. A stopper of the kind defined by claim 1 in which the upper portion of said tubular 65 head forms a knob having its greater diameter near its upper portion to permit the head to be readily grasped by the hand.

4. A stopper of the kind defined by claim 1 in which the upper portion of the head is 70 of substantially the shape of an inverted frusto cone.

5. A stopper of the kind defined by claim 1 in which said rod is pointed to permit the same to be readily inserted through the plug 75 for the purpose of forming the perforation in said plug.

6. A sprinkling stopper comprising a substantially cylindrical cork plug having a substantially flat upper surface, a tubular wooden head arranged on said plug and having a substantially flat lower surface engaging the head of the plug, an annular skirt forming an extension of said tubular head and snugly engaging the outer surface 80 of the head portion of said plug, said plug being provided with a passageway extending therethrough and in alignment with the bore of the tubular head, the upper portion of said tubular head being of substantially 85 inverted frusto conical shape and being provided with a recess merging into the bore of said tubular head, and a removable metal rod passing through the bore of the tubular head and through the passageway of the 90 plug for closing the same and provided with a head resting in said recess for sealing the bore.

7. A stopper of the kind defined by claim 6 in which the rod is pointed to permit the 100 same to form the passageway in said plug.

8. A stopper of the character specified in claim 1, in which a portion of the headed rod, adjacent the head on said rod is provided exteriorly with corrugations to engage 105 the inner surface of the bore of said tubular head and prevent accidental removal of said rod.

In testimony whereof I affix my signature.
JAMES OTIS WILLIAMSON.
